(57) **CLAIM**

The ornamental design for a track rail for motion guide device, as shown and described.

DESCRIPTION

FIG. 1 is a front elevational view of a track rail for motion guide device, showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a cross-sectional view thereof, taken along line 7-7 of FIG. 5.

FIG. 8 is an enlarged view thereof, showing the section marked 8-8 of FIG. 7.

FIG. 9 is a cross-sectional view thereof, taken along line 9-9 of FIG. 5.

FIG. 10 is an enlarged cross-sectional view thereof, taken along line 9-9 of FIG. 5.

FIG. 11 is a cross-sectional view thereof, taken along line 11-11 of FIG. 5; and,

FIG. 12 is an enlarged cross-sectional view thereof, taken along 11-11 of FIG. 5.

The broken lines illustrate environmental structure and form no part of the claimed design. The dot-dash lines form boundaries of the claimed design and form no part thereof.
